UNITED STATES PATENT OFFICE.

GEORGE LEESON, OF LAKE CITY, MINNESOTA.

WASHBOILER.

SPECIFICATION forming part of Letters Patent No. 707,126, dated August 19, 1902.

Application filed February 17, 1902. Serial No. 94,548. (No model.)

To all whom it may concern:

Be it known that I, GEORGE LEESON, a citizen of the United States, residing at Lake City, in the county of Wabasha and State of Minnesota, have invented a new and useful 5 Washboiler, of which the following is a specification.

This invention relates to devices to be employed in connection with washboilers; and 10 it consists in a device adapted to be placed within the boiler whereby the clothes may be more thoroughly subjected to action of the hot water or supported in a position to be subjected to the action of steam above the water 15 and also in a position to be drained after being boiled or steamed, as hereinafter shown and described and specifically pointed out in the claims.

In the drawings illustrative of the invention and in which like characters are employed to designate corresponding parts, Figure 1 is a perspective view of the device 20 complete and removed from the boiler. Fig. 2 is an enlarged transverse section on the line 25 xx of Fig. 1. Fig. 3 is a longitudinal section of a washboiler and of the improved device arranged therein, also in longitudinal section.

The device consists in a base-plate 1, having a series of perforations 2 therein, arranged 30 in rows, preferably at equal distances apart. The plate will conform closely to the interior of the washboiler, (represented in outline at 3,) so that when placed therein it will form substantially a false bottom thereto. The sides 35 of the plate 1 will be turned upward, as shown at 4, to assist in supporting the clothes and will also be provided with handles at the ends by which it may be lifted from and adjusted in the boiler. Each handle is formed with 40 two side members 5 and a transverse member 6, with the lower ends of the side members turned off laterally and engaging ears 7, in which they are pivoted, as shown. The ends of the side members, outside the ears 7, are 45 bent inward toward the center of the boiler, as at 8, and rest in contact with the ears or the plate 1 to form stops to limit the inward movement of the handles and prevent them from being folded inward, but which will not 50 prevent them from being turned outward, as will be readily understood. By this means the handles will never fall inward into the

hot water in the boiler or become submerged therein or covered by the clothes, but will always remain in a substantially upright position and projecting out of the water convenient to the hand of the operator. The handles will not be long enough to project upward above the upper line of the body of the boiler, so that their presence will not interfere with 60 the placing of the cover in position on the boiler. At one or more points the side members 5 of the handles are formed into hooks 9, adapted to engage the upper rim of the boiler to afford means for suspending the plate 1 at 65 one or more points above the bottom of the boiler to support the clothes above the water-line in the boiler to permit them to be subjected to the action of the steam or for the purpose of drainage, as may be required. As 70 many of these hooks 9 may be employed as may be required; but generally two in each side member, as shown, will be sufficient.

Upon the under and upper surface of the plate 1 are a series of guard-strips 10, each 75 strip being concave on one side and convex on the other and perforated at suitable intervals and arranged to cover the perforations 2, as shown, the guard-strips on the upper surface of the plate adapted to form guards 80 to support the clothes and prevent them from shutting off or clogging the perforations in the plate 1, while the guard-strips on the lower surface of the plate serve the double purpose of legs to the plate to hold it up away from 85 the bottom of the boiler, and also to provide for the free circulation of the water beneath the plate and through the perforations therein. It will not be necessary to provide the guard-strips both above and below the same 90 perforations. Hence, as will be seen in Fig. 2, where the guard-strips are arranged above the perforations none are arranged beneath that particular set of perforations, and then, on the contrary, where the guard-strips are 95 arranged beneath the perforations no guard-strips are arranged above that particular set of perforations. Thus no unnecessary guard-strips are employed. The guard-strips, in addition to the functions already described, 100 perform another and important function in that they serve as longitudinal braces to the plate 1, which is especially important when the latter is suspended at an elevation, sup-

porting the clothes thereon. The said plate being to some extent weakened by the perforations therein would be liable to bend and yield under the pressure if it were not strongly braced, and the guard-strips thus in addition to the functions already ascribed to them act as braces, whereby the brace-plate is enabled to support any weight that may be placed thereon without bending or yielding to the pressure. By this simple arrangement the clothes are supported in the boiler in a very convenient position to be handled, either for entire removal or to suspend them in the boiler intermediate of its depth, as before described.

Having thus described my invention, what I claim as new is—

1. A washboiler attachment comprising a plate conforming to the interior of the boiler and having parallel rows of alined perforations arranged longitudinally, said plate being provided with perforated semitubular guard-strips secured longitudinally to cover the rows of perforations therein, said guard-strips

being disposed alternately on the upper and 25 under sides of said plate and serving to brace the same longitudinally, and part of said guard-strips being disposed on the under side of said plate to form supports for the latter, substantially as set forth.

2. A washboiler attachment having means at the ends thereof whereby it may be elevated and suspended at various points of elevation, said plate being provided with longitudinally-disposed rows of perforations and with longitudinally-disposed guard-strips covering said perforations and serving also as braces to prevent the plate from flexing or yielding under the weight of the clothes disposed thereon, substantially as set forth.

In testimony that I claim the foregoing as my own I have hereto affixed my signature in the presence of two witnesses.

GEORGE LEESON.

Witnesses:

OTTO E. ANDERSON,
S. O. SEVALL.
